AUTOMOBILE FENDER

Virgil M. Exner, and Maurice F. Baldwin, Birmingham, Mich., assignors to Chrysler Corporation, Highland Park, Mich., a corporation of Delaware

Application September 2, 1955, Serial No. 37,770

Term of patent 7 years

(Cl. D14—6)

Fig. 1 is a side elevational view of an automobile fender showing our new design;

Fig. 2 is a top plan view thereof;

Fig. 3 is a rear elevational view of the fender; and

Figs. 4, 5, 6 and 7 are sectional views taken on the lines 4—4, 5—5, 6—6 and 7—7, respectively, of Fig. 1.

We claim:

The ornamental design for an automobile fender, substantially as shown.
